UNITED STATES PATENT OFFICE.

AUGUST ARENS, OF NEW BRITAIN, CONNECTICUT, ASSIGNOR TO P. & F. CORBIN, OF NEW BRITAIN, CONNECTICUT, A CORPORATION OF CONNECTICUT.

ENTRANCE-DOOR LOCK.

971,340.

Specification of Letters Patent. Patented Sept. 27, 1910.

Application filed November 27, 1909. Serial No. 520,100.

To all whom it may concern:

Be it known that I, AUGUST ARENS, a citizen of the United States, residing at New Britain, county of Hartford, State of Connecticut, have invented certain new and useful Improvements in Entrance-Door Locks, of which the following is a full, clear, and exact description.

My invention relates to locks, and particularly to improved features of construction in that type of lock illustrated in the Phelps Patent No. 722,619, of March 10, 1903.

The object of the present invention is to provide, in the type of lock referred to, certain improved features of construction whereby the outside knob may be dogged in a unique manner against rotation (for the purpose of operating the latch mechanism) and whereby, even though said outer knob be dogged, entrance from the outside may still be effected by means of a proper key.

The invention also comprehends in its construction apparatus for actuating a dead bolt from either the inside or outside of a door at any time, said dead bolt being actuated by the same instrumentality as is employed for operating the latch mechanism from the outside of the door when the outer knob is dogged, *viz.*, a key.

The invention has great utility in connection with entrance doors, particularly entrance doors for public institutions and stores wherein the locks are subjected to much use.

In the lock of the patent to which I have above referred the dogging mechanism for the outer knob is controlled wholly by an exposed operating ring located so closely to the shell of the inside handle that it sometimes happens that a person passing from the inside to the outside of a door accidentally and unintentionally turns the dog operating ring simultaneously with turning the inner knob, which act either dogs or releases the outer knob as the case may be. Obviously, if it has been the intention of the owner of the lock to dog the outer knob so that entrance can not be had from the outside without proper announcement or without the use of a proper key, such intention would be defeated by the accidental manipu-

lation and releasing of the dog operating ring above referred to.

My present invention eliminates all danger of accidental or unintentional operation of the dog actuator and dog. Not alone does the present invention accomplish this but it also prevents all mischievous tampering with the lock in such a way as to dog or release the outer knob as the case may be.

These and other advantages will be apparent to the mechanic skilled in the art by a reading of the following description and an examination of the accompanying drawings, in which—

Figure 1 is a plan view; Fig. 2 is in the main a section on the line $x-x$ of Fig. 1, certain parts being shown in elevation; Fig. 3 is an elevation of certain parts taken on the plane on the line $y-y$ of Fig. 2; Fig. 4 is a section on the plane of the line $z-z$ of Fig. 2, certain parts being shown in elevation, and certain parts being omitted; Fig. 5 is a plan view of a detail (the central spindle) detached; Figs. 6, 7, 8, 9 and 10 are end views of other details; Fig. 11 is a fragmentary side view of another detail, partly in section; Fig. 12 is a similar view of still another detail; Fig. 13 is a view of the outer side of the inner section of one of the knobs; Fig. 14 is a side elevation of another detail; Fig. 15 is an end view of another detail; Fig. 16 is an end view of the detail shown in Fig. 14; Fig. 17 is a side elevation of the forward end of the lock shown in Fig. 1.

For a detailed description of most of the features of construction employed in the present lock, reference may be made to the Phelps patent above referred to, also Phelps Patent No. 834,994. As to such features as are described in said patents, I shall refer to the same herein in general terms only, devoting the detail description to such features of improvement as have been invented by me.

The lock in its preferred form includes the main supporting frame 1, having the face plate 2 at its front end and having the knob supporting bearings 3—4 near its rear end.

5 is a latch bolt.

6 is a dead bolt.

7 is an actuator for a latch dog, whereby

when the door is closed the latch 5 can not be pushed back by the insertion of a thin blade or other appropriate instrument into the space between the edge of a door (bearing said lock) and the door casing,—a method of unlawful entry commonly practiced.

In the present instance 8 represents the inner knob and 9 the outer knob of the lock. 10 These knobs are provided with inwardly projecting shanks 8^a and 9^a respectively.

10—11 are independent roll backs both arranged to engage the yoke 12 of the latch bolt, whereby said latch bolt may be retracted by turning either knob, said roll backs being suitably connected with the shanks of said knobs 8—9 respectively, one suitable method of connecting said parts being disclosed in the patent first above referred to. The roll back 11 is so mounted that when in one position it may turn freely with the shank of the knob 9 but when said roll back is in another position it engages in notches in the fixed frame of the lock, and hence can not be turned. Under such conditions it is plain that the shank 9^a can not be turned and hence at such a time the outer knob 9 will be "dogged". This construction and operation is more fully disclosed in the earlier patents referred to.

50 is a single armed roll-back mounted upon an internal spindle 13 which is controlled by a suitable key which may be inserted in the outer end of either knob, both 35 knobs having the usual pin-tumbler lock therein later referred to. The roll-back 50 is adapted to perform the single function of operating the dead bolt 6, the intermediate connecting mechanism between said dead 40 bolt and said roll-back 50 being similar to that shown, described and claimed in Phelps Patent No. 722,619.

14—15 are locks arranged to be carried by and within the knobs 9—8 respectively, said 45 locks in this particular instance being of the pin-tumbler type. The plug end of each of these locks is of special formation, each being different, hence I will describe the same separately.

50 The inner end 14^a of the plug of lock 14 (for the outer knob) has a central bore which rotates on the end of the spindle 13, the corners of the latter being rounded off somewhat to avoid undue wear. The spindle 13 receives its support at one end in this plug. To provide a proper bearing, and to perform another function hereinafter more fully described, the plug of the lock 14 extends inwardly, as at 14^a, Fig. 4. One side 55 of this plug end 14^a is cut away, as indicated at 14^b, (Fig. 15) to afford a receiving space for a pin 16 projecting laterally from an adjacent part of the spindle 13.

The plug of the lock 15 has a tubular ex-

tension 15^a but in this instance said tubular extension is in the form of a sleeve rotatably mounted upon the solid end of the plug, said solid part being shown at 17 (Fig. 14).

17^a is a pin projecting laterally from the solid inner end 17 of the plug of lock 15, said pin end standing in a slot arranged transversely in the wall of the sleeve extension 15^a so that said sleeve extension may have a limited amount of rotary movement 75 relatively to the solid part 17 of the plug, and vice versa. The outer end of the sleeve extension 15^a of the plug has a specially formed spiral cam, which begins approximately at the point indicated at 18, and 80 terminates at the point indicated at 19. As a matter of fact the low part of said spiral groove terminates or communicates with a back-set notch, as clearly shown in the drawings, the function of which will later be 85 seen. A laterally projecting pin 20 (Fig. 4) on spindle 13 bears against the wall of the spiral cam at the inner end of the sleeve extension 15^a, the adjacent end of the spindle 13 being supported in the round bore of 90 said sleeve extension in a manner similar to the support for the opposite end of the spindle 13. 21 is a single armed roll-back, which lies adjacent to the roll-back 50 when the parts are assembled, the single arm of 95 said roll-back 21 performing the function of coupling the key-actuated spindle 13 with the latch slide for the purpose of retracting the latch bolt by means of a key. This particular roll-back construction is described in 100 more detail in the former Phelps Patent No. 722,619.

The spindle 13 has an intermediate round portion 13^a and has a stop shoulder 13^b at one side of said round portion. The shift- 105 able roll-back 11 always stands adjacent to the rounded portion 13^a, being prevented from moving to one side thereof by the stop shoulder 13^b and to the other side by a friction held sleeve 22, which may be slipped 110 over the spindle 13 from one end. One or both of the pins 16—20 may be made removable. The roll-backs 50—21 each have an opening so shaped that while the same may slide upon the spindle 13 neither of 115 them can rotate independently thereof. The inner end of the tubular knob bearing 3 is notched at 23 to receive the shiftable roll-back 11 when it is desired to dog the outer knob 9 against rotation.

24 is an expansion spring located between the inner end of the plug extension 14^a and the friction sleeve 22, suitable washers being provided as shown, if desired, to afford a proper support for the ends of said spring. 125 The function of this spring 24 is to gently press the spindle 13 to the right as viewed in Fig. 2 so as to hold the pin 20 against the

spiral cam at the inner end of the sleeve extension 15^a.

14^c is an offset on the outside of the plug 14^a while 14^d is a stop pin on the inner wall 5 of the knob 9 in the path of movement of the offset shoulder 14^c, the purpose of said offset and pin being to limit the rotation of the plug end 14^a so that it will not override any of the parts. It will be understood that 10 the knob 8 is always free to turn to withdraw the latch.

Operation: It will be understood that, like the previous locks referred to, the present construction may be employed in a similar manner in many respects. For example, the latch bolt 5 may be retracted by the turning of either of the knobs 8 or 9 or by the turning of the spindle 13 by means of a suitable key in the proper direction to cause the roll-back 20 21 to engage the latch slide. In the present case, however, the key-controlled spindle may be rotated by a suitable key in such a manner as to advance or retract the dead bolt, a feature not possible with the spindle 25 shown in the lock of the patent previously referred to. In the present instance, too, it is possible through the medium of the same spindle to dog and release the outer knob from the inside of the door to which the lock 30 35 is applied. The construction is also such that no matter what function is to be performed by the key-controlled spindle, it is possible at any time to impart the desired motion to the lock by the key and then withdraw the same. In performing these functions the operation is as follows: Assuming the parts are as shown in the drawings with the dead bolt withdrawn and both knobs free to turn. If it is desired simply to "dog" 40 the outer knob, the operator has but to turn counter clockwise the sleeve extension 15^a by the insertion of a suitable key in the lock 15. By turning this sleeve in a counter clockwise direction the spiral cam thereon causes 45 the pin 20 and spindle 13 to move to the left, as viewed in Fig. 2. One complete revolution of the sleeve 15^a accomplishes this shifting of the spindle to a sufficient extent to move the roll-back 11 into the notches 23 50 at the inner end of the stationary knob bearing 3. The key may then be withdrawn. This act of shifting the spindle and roll-back 11 "dogs" the outer knob 9 so that the same can not be turned and the latch 5 can 55 not be retracted thereby. The insertion of the key in the inner knob and a clockwise complete revolution will restore the parts to the original position, the spring 24 aiding in this operation. If at any time during the 60 period when the outer knob is "dogged" it is desired to enter from the outside, the holder of the suitable key inserts it in the lock in knob 9 and turns the same in a counter clockwise direction causing one side

of the clearance recess 14^b to engage pin 16 65 on the spindle 13 so that a continued rotation of the key (and plug of lock 14) in the same direction will rotate spindle 13 so as to retract the latch through the medium of the roll-back 21. If it is desired to not only 70 "dog" the outer knob, but also to advance the dead bolt 6, this may be accomplished from the inside by inserting a key and turning it as first described one complete revolution counter clockwise to first dog the outer 75 knob; then, by continuing this revolution the wall at the end of the aforesaid set-back notch will engage the pin 20 and turn the spindle in a direction to advance the dead bolt 6 through the medium of roll-back 50. 80 A partial clockwise rotation of the key will bring it back into proper position for removal, leaving the outer knob dogged and the dead bolt advanced. If one desires to enter from the outside under such conditions he has but to insert a suitable key in the lock in the outer knob 9 and turn it in a counter clockwise direction as before, causing one side of the clearance notch 14^b to engage pin 16, whereupon continued rotation 85 imparts to the spindle corresponding rotation so that the dead bolt 6 will first be withdrawn by action of the roll-back 50. Continued rotation in the same direction causes the retraction of the latch slide (the outer 90 knob itself being still dogged) through the medium of the roll-back 21.

Assuming the parts are in the position shown in the drawings, and the user of the lock simply wishes to go outside and lock 100 the door from the outside by means of the dead bolt 6, he has but to insert the key in the lock in the outer knob and turn it in a clockwise direction, bringing one side wall of the notch 14^b into engagement with the 105 pin 16, turning the spindle 13 thereby in the same direction until the dead bolt 6 is projected through the medium of the roll-back 50. By then reversing the direction of rotation of the key and bringing it to its 110 original position, said key may be withdrawn.

To withdraw the dead bolt from the outside (the outer knob not being dogged in this case) the key may be again inserted and 115 turned in a counter clockwise direction until the opposite side of the notch 14^a engages the pin 16 whereupon continued rotation withdraws the dead bolt through the medium of the same roll-back 50.

From the foregoing it will be seen that all of the functions necessary in any single entrance door lock are capable of performance here and the modified and added features of construction, which have been applied by me to the aforesaid well known Phelps' locks, in no way impair or interfere with the action of the parts as pro-

vided in said Phelps' locks. In the present construction there is no possibility of unintentional, accidental or mischievous dogging or undogging of the outer knob or locking or unlocking of the door, since it can only be accomplished by one who has sufficient authority to hold a proper key.

What I claim is:

1. In a lock, a latch bolt, a dead bolt, two knobs arranged to stand on opposite sides of said lock and independently operable, a roll-back for each knob operatively connected with said latch, another roll-back operable independently of the knobs and also operatively connected with said latch, still another roll-back operatively connected with said dead bolt, all of said roll-backs being arranged side by side, a spindle passing through all of said roll-backs and key-controlled means carried by each knob and operable independently thereof for operating said spindle.

2. In a lock, a latch bolt, a dead bolt, two knobs arranged to stand on opposite sides of said lock and independently operable, a roll-back for each knob operatively connected with said latch, another roll-back operable independently of the knobs and also operatively connected with said latch, still another roll-back operatively connected with said dead bolt, all of said roll-backs being arranged side by side, and key-controlled means carried by each knob and operable independently thereof for operating said spindle, said spindle having a longitudinal movement, one of the first mentioned roll-backs being movable laterally by the longitudinal movement of the spindle, said roll-back being free when the spindle stands in one position and held against rotation when the spindle stands in another position, said spindle-operating means at one end being constructed to impart either rotary or longitudinal movement to said spindle.

3. In a lock, a latch bolt, a dead bolt, two oppositely arranged independent knobs, both of said knobs being independently connected with said latch bolt, a roll-back for the latch bolt independent of the knobs, a roll-back for the dead bolt independent of the knobs, said roll-backs being arranged side by side, a spindle for operating said roll-backs by a rotary movement, means carried by the spindle to lock one of the knobs against rotation by a longitudinal movement of the spindle, key-operable means carried by one knob for imparting both a rotary and a longitudinal movement to said spindle, and key-operated means carried by the other knob for imparting rotary movement only to said spindle.

4. In a lock, a latch bolt, a dead bolt, opposite independent knobs, a roll-back con-

nection between each knob and said latch bolt, another roll-back operable independently of the knobs and operatively connected with the latch bolt, and still another roll-back operable independently of the knobs and operatively connected with the dead-bolt, means for locking one of said knobs against rotation, and key-operable means concentric with the knobs and accessible by a key entered through the end of either knob for operating the last two mentioned roll-backs.

5. In a lock, a latch bolt, a dead bolt, opposite independent knobs, a roll-back connection between each knob and said latch bolt, another roll-back operable independently of the knobs and operatively connected with the latch bolt, and still another roll-back operable independently of the knobs and operatively connected with the dead-bolt, means for locking one of said knobs against rotation, and key-operable means concentric with the knobs and accessible by a key entered through the end of either knob for operating the last two mentioned roll-backs, said key-operable means at one side of the lock being included in the means for locking one of the knobs against rotation.

6. In a lock, an inner and an outer knob, a latch bolt, a dead bolt, independent roll-back connections between both knobs and the latch bolt whereby said latch bolt may be operated by either knob independently, two roll-backs for operating the latch bolt and dead bolt independently of the knob mechanism, key mechanism having a connection through the inner knob for dogging the outer knob to hold the same against rotation, and key mechanism having a connection through the outer knob with the last mentioned roll-backs to operate the same independently of the roll-back for the outer knob.

7. In a lock, two oppositely arranged independently operable knobs, with means for dogging one of said knobs, a latch bolt, a dead bolt, said latch bolt being operable by either of said knobs independently, a roll-back independent of both knobs for operating the latch, another roll-back for operating said dead bolt, means operable through the inner knob for dogging the outer knob against rotation, and key-operable means having a connection through the inner knob for dogging the outer knob and for operating the dead-bolt, and another key-operable means having a connection through the outer knob for operating the latch bolt and dead bolt.

8. In a lock, an inner and an outer knob, a latch bolt, a dead bolt, independent roll-back connections between both knobs and the latch bolt whereby said latch bolt may be operated by either knob independently,

- two roll-backs for operating the latch bolt and dead bolt independently of the knob mechanism, and key-controlled mechanism having a connection through both knobs for 5 operating the latch bolt and dead bolt from either side of the door and independently of the knob roll-backs.
9. In a lock, a latch bolt, a dead bolt, two oppositely arranged independent knobs, a 10 roll-back for each operatively connected with said latch bolt, another roll-back independent of the knobs for operating said latch bolt, another roll-back independent of the knobs for operating the dead bolt, a 15 single spindle supporting the last two roll-backs for rotating the same and operatively connected with one of the first mentioned roll-backs to move the same laterally, and key-operable means for imparting both rotary and longitudinal movement to the 20 spindle, said key-operable means including connections through one knob, other key-operable means including connections through the other knob for imparting rotary movement to the spindle.
10. In a lock, a latch bolt, a dead bolt, two oppositely arranged independent knobs, a roll-back for each operatively connected with said latch bolt, another roll-back independent of the knobs for operating said latch bolt, another roll-back independent of the knobs for operating the dead bolt, a single 30 spindle supporting the last two roll-backs for rotating the same and operatively connected with one of the first mentioned roll-backs to move the same laterally, and key-operable means for imparting both rotary and longitudinal movement to the spindle, said key-operable means including connections through one knob, and other key-operable means including connections through the other knob for imparting rotary movement to the spindle independently of the longitudinal position of said spindle.
- 45 11. In a lock, a latch bolt, a dead bolt, two knobs for operating said latch-bolt independently, a dogging device for one of said knobs, said dogging device being operable by a key insertible in the opposite knob, key-mechanism in each knob, and connections between said key-mechanism and said bolts whereby said latch bolt and said dead bolt may be operated by the insertion of a key in either knob.
- 55 12. In a lock, a latch bolt, two oppositely arranged independently operable knobs, connections between each of said knobs and said latch bolt, independent key-controlled mechanism carried by each knob, a connection between each of said key-controlled mechanisms and the latch bolt whereby said latch bolt may be operated by either key-controlled mechanism at any time, and a connection between one of said key-controlled mechanisms and the opposite knob for dogging the latter against rotation.
13. In a lock, a latch bolt, two oppositely arranged independently operable knobs, connections between each of said knobs and said latch bolt, independent key-controlled mechanism carried by each knob, a connection between each of said key-controlled mechanisms and the latch-bolt whereby said latch bolt may be operated by either key-controlled mechanism at any time, and a connection between one of said key-controlled mechanisms and the opposite knob for dogging the latter against rotation, a dead bolt, and means of connection between both of said key-controlled mechanisms and said dead bolt whereby said dead bolt may be operated at any time by either of said key-controlled mechanisms.
14. In a lock, a latch bolt, a dead bolt, inner and outer independently operable knobs, a roll-back for each knob operatively connected with said latch bolt, a roll-back operable independently of the knobs and means for operatively connecting the same with said latch, another roll-back and means for operatively connecting the same with said dead bolt, a spindle supporting the last two roll-backs, and key-actuated mechanism carried by the inner knob in combination with means associated therewith to first 90 dog the outer knob against rotation when the spindle is turned in one direction and to then project the dead bolt upon a further turn of said spindle in the same direction.
15. In a lock, a latch bolt, a dead bolt, inner and outer independently operable knobs, a roll-back for each knob operatively connected with said latch, a roll-back operable independently of the knobs, and means for operatively connecting the same with said latch bolt, another roll-back and means for operatively connecting the same with said dead bolt, a spindle supporting the last two roll-backs, and key-actuated mechanism carried by the inner knob in combination with means associated therewith to first 95 dog the outer knob against rotation when the spindle is turned in one direction and to then project the dead bolt upon a further turn of said spindle in the same direction.
- 100 16. In a lock, a latch bolt, a dead bolt, inner and outer independently operable knobs, a roll-back for each knob operatively connected with said latch, a roll-back operable independently of the knobs, and means for operatively connecting the same with said latch bolt, another roll-back and means for operatively connecting the same with said dead bolt, a spindle supporting the last two roll-backs, key-actuated mechanism carried by the inner knob but rotatable independently thereof.
- 110 17. In a lock, a latch bolt, a dead bolt, inner and outer independently operable knobs, a roll-back for each knob operatively connected with said latch, a roll-back operable independently of the knobs, and means for operatively connecting the same with said latch bolt, another roll-back and means for operatively connecting the same with said dead bolt, a spindle supporting the last two roll-backs, key-actuated mechanism carried by the inner knob but rotatable independently thereof.
- 115 18. In a lock, a latch bolt, a dead bolt, inner and outer independently operable knobs, a roll-back for each knob operatively connected with said latch, a roll-back operable independently of the knobs, and means for operatively connecting the same with said latch bolt, another roll-back and means for operatively connecting the same with said dead bolt, a spindle supporting the last two roll-backs, key-actuated mechanism carried by the inner knob but rotatable independently thereof.
- 120 19. In a lock, a latch bolt, a dead bolt, inner and outer independently operable knobs, a roll-back for each knob operatively connected with said latch, a roll-back operable independently of the knobs, and means for operatively connecting the same with said latch bolt, another roll-back and means for operatively connecting the same with said dead bolt, a spindle supporting the last two roll-backs, key-actuated mechanism carried by the inner knob but rotatable independently thereof.
- 125 20. In a lock, a latch bolt, a dead bolt, inner and outer independently operable knobs, a roll-back for each knob operatively connected with said latch, a roll-back operable independently of the knobs, and means for operatively connecting the same with said latch bolt, another roll-back and means for operatively connecting the same with said dead bolt, a spindle supporting the last two roll-backs, key-actuated mechanism carried by the inner knob but rotatable independently thereof.

- by the inner knob in combination with means associated therewith to first dog the outer knob against rotation when the spindle is turned in one direction and to then project the dead bolt upon a further turn of said spindle in the same direction, said means comprising a spiral cam carried by the inner knob but rotatable independently thereof, and means of connection between said cam and said spindle to rotate said parts together when said cam is turned in an opposite direction to first release the outer knob to permit the same to be turned freely and to then withdraw said dead bolt.
- 15 17. In a lock, two oppositely arranged independently operable knobs, a latch bolt operatively connected with said knobs for independent operation thereby, a dead bolt, roll-back mechanism for operating said latch bolt and dead bolt independently of either knob, key-controlled mechanism carried by each knob, means of operative connection between said key-controlled mechanism and said latch bolt and dead bolt whereby
- 20

either bolt may be operated by a key from either side of the lock as well as by a knob on either side of said lock.

18. In a lock, two oppositely arranged independently operable knobs, a latch bolt operatively connected with each knob for independent operation thereby, a dead bolt, roll-back mechanism for operating said latch bolt and dead bolt independently of either knob, key-controlled mechanism carried by each knob, means of operative connection between said key-controlled mechanism and said latch bolt and dead bolt whereby either bolt may be operated by a key from either side of the lock as well as by a knob on either side of said lock, and a dogging mechanism for one of said knobs, said dogging mechanism being operated by the key-controlled mechanism carried by the opposite knob.

AUGUST ARENS.
